US0D1110867S

(12) **United States Design Patent** (10) **Patent No.:** **US D1,110,867 S**
(45) **Date of Patent:** ** *Feb. 3, 2026

(54) **AIRCRAFT TOTAL AIR TEMPERATURE SENSOR**

(71) Applicant: **Rosemount Aerospace Inc.**, Burnsville, MN (US)

(72) Inventors: **Chad Herman**, Excelsior, MN (US); **Rudy Pitera**, Inver Grove Heights, MN (US); **Scott Isebrand**, Minneapolis, MN (US)

(73) Assignee: **Rosemount Aerospace Inc.**, Burnsville, MN (US)

(*) Notice: This patent is subject to a terminal disclaimer.

(**) Term: **15 Years**

(21) Appl. No.: **29/928,315**

(22) Filed: **Feb. 9, 2024**

(57) **CLAIM**

The ornamental design for an aircraft total air temperature sensor as shown and described.

DESCRIPTION

FIG. 1 is a front isometric view;

FIG. 2 is a rear isometric view;

FIG. 3 is a right side view;

FIG. 4 is a left side view; and

FIG. 5 is a front elevational view;

FIG. 6 is a rear elevational view;

FIG. 7 is a top plan view; and,

FIG. 8 is a bottom plan view.

The broken lines shown are included for the purpose of illustrating portions of the aircraft total temperature sensor that form no part of the claim.

1 Claim, 4 Drawing Sheets
